CONVERSION OF HYDROCARBON OIL

Alvin Engelstein, Chicago, Ill., assignor to Universal Oil Products Company, Chicago, Ill., a corporation of Delaware

Application February 27, 1936, Serial No. 65,995

2 Claims. (Cl. 196—49)

This invention particularly refers to an improved process wherein selected fractions of a crude oil, containing a substantial amount of straight-run gasoline, are selectively cracked to 5 produce high yields of motor fuel of good anti-knock value, in an economic manner.

A feature of the invention comprises reforming motor fuel fractions contained in the charging stock, for the purpose of improving their anti-knock value, utilizing the excess heat contained 10 in the resulting hot conversion products for distilling the charging stock by commingling the same therewith and thereby cooling the re-formed products to the desired degree by the heat ex- 15 change with the charging stock.

In combination with the fractional distillation 20 of crude oil containing low boiling hydrocarbons within the boiling range of motor fuel, the invention contemplates selectively cracking various fractions of charging stock and intermediate liquid conversion products of the process of selected boiling point range, to produce high yields 25 of motor fuel of good anti-knock value and minor yields of marketable fuel oil and uncondensable gas. As an alternative, the process may be operated to produce motor fuel, uncondensable gas, 30 and substantially dry coke.

In one embodiment, the invention comprises introducing crude charging stock, containing a considerable portion of materials within the boiling 35 range of motor fuel into a separating and fractionating column wherein it is separated by substantial vaporization and fractionation into three fractions comprising a low boiling cut such as gasoline, an intermediate fraction such as gas oil and/or kerosene, and heavy topped crude. The low boiling fractions are removed as fractionated vapors from said column, subjected to condensation, the resulting distillate supplied in regulated 40 quantities to the reforming coil wherein it is subjected to relatively severe conversion conditions of cracking temperature and substantial superatmospheric pressure, the highly heated products discharged from the reforming coil, 45 commingled with the crude charging stock, and the commingled materials introduced into the separating and fractionating column. The heat for effecting fractional distillation of the crude oil is derived from the heated products of the 50 reforming operation and the charging stock serves to cool the reformed products sufficiently to prevent any excessive further conversion thereof. As can readily be seen, any desired quantity of gasoline from the topping and reforming operation 55 may be recycled to the reforming coil to obtain

sufficient heat for topping and to produce a final motor fuel product of the desired anti-knock value.

Reflux condensate, comprising intermediate fractions of the crude and components of the vaporous conversion products boiling above the range of the desired reformed motor fuel product, is removed from the fractionating column, subjected to conversion conditions of cracking temperature and superatmospheric pressure in a 5 separate heating coil and communicating reaction chamber, both vapors and liquid products withdrawn in commingled state from the reaction chamber and introduced into a reduced pressure vaporizing zone, the resulting non-vaporous 10 residual liquid recovered from the vaporizing chamber, vaporous products separately withdrawn from the vaporizing chamber and introduced into a separate fractionating column wherein their 15 insufficiently converted components are condensed 20 as reflux condensate, fractionated vapors of the desired end boiling point removed from the last mentioned fractionating column, subjected to condensation and the resulting distillate recovered, reflux condensate separately withdrawn 25 from the last mentioned fractionating column and returned to said separate heating coil for cracking 30 together with said intermediate fractions from the reforming and topping operation. High boiling oils comprising the high boiling components 35 of the crude and residual liquid conversion and polymerization products from the reforming operation are removed from the lower portion of the separating column, subjected to relatively mild conversion conditions of cracking temperature and superatmospheric pressure in another 40 separate heating coil and the heated products therefrom introduced, all or in part, into the vaporizing chamber or the reaction chamber or, in part, to both.

The accompanying diagrammatic drawing illustrates one specific form of apparatus in which the invention may be carried out. Charging stock for the process, preferably comprising crude petroleum or similar wide-boiling range oil containing a substantial quantity of motor fuel or motor fuel fractions, is supplied through line 1 and valve 2 to pump 3 by means of which it is fed through line 4, valve 5 and line 21 into separating and fractionating column 6. The charging stock is commingled in line 21 with hot conversion products from heating coil 19 whereby it is heated sufficiently to effect its substantial vaporization in column 6 and serves to partially cool and retard or arrest conversion of the prod- 55

ucts from heating coil 19. The commingled materials supplied to column 6 are separated therein, in the case here illustrated, into three selected fractions, the nature of which will be later 5 described.

The overhead fractionated product from column 6 comprises components of the charging stock and conversion products from heating coil 19 boiling within the range of the desired final 10 motor fuel product of this stage of the system and is directed, together with the gaseous products of this stage of the system, through line 7 and valve 8 to condensation and cooling in condenser 9, wherefrom the resulting distillate and 15 gas pass through line 10 and valve 11 to collection and separation in receiver 12. The uncon- 20 densed gas may be released from receiver 12 through line 14' and valve 15'. Distillate is withdrawn from the receiver through line 13 and is 25 directed, in part, through valve 14 to storage or elsewhere, as desired. A regulated portion of the distillate removed from receiver 12 is diverted from line 13 through line 13' and valve 15 to pump 16 by means of which it is supplied through line 17 and valve 18 to heating coil 19.

When desired, regulated quantities of the distillate collected in receiver 12 may be recirculated by well known means (not shown) to the upper portion of column 6 to serve as a refluxing and 30 cooling medium in this zone for assisting fractionation of the vapors and to maintain the desired vapor outlet temperature therefrom.

Heat is supplied to coil 19 from a suitable furnace 20 by means of which the oil passing through 35 the heating coil is heated to a sufficiently high cracking temperature to effect a substantial improvement in its motor fuel characteristics, particularly with respect to anti-knock value, without excessively altering its boiling range. A relatively high superatmospheric pressure is prefer- 40 ably employed at the outlet from heating coil 19 and the highly heated products from this zone are directed through line 21 and valve 21' to column 6. Preferably, the pressure imposed upon 45 the stream of heated products from heating coil 19 is substantially reduced as they pass through valve 21'. This pressure reduction serves to assist cooling and retard conversion of the heated products and preferably, as previously indicated, additional cooling of the heated products is obtained by commingling the same in line 21 with 50 the charging stock supplied to column 6.

Selected intermediate fractions of the charging stock and conversion products from heating coil 55 19 supplied to column 6 are withdrawn as one or a plurality of side streams from a suitable intermediate point or points in column 6, provision being made, in the case here illustrated, for removing this material from column 6 through line 22 wherefrom it is directed through valve 23 to pump 24. Pump 24 supplies these intermediate fractions through line 25, valve 26 and line 27 to heating coil 54.

Reflux condensate from fractionator 48 is also 65 supplied to heating coil 54, as will be later more fully described, and the commingled oils passing through this zone are heated to the desired crack- 70 ing temperature preferably at a substantial superatmospheric pressure by means of heat supplied from furnace 55. The heated products are dis- charged from heating coil 54 through line 56 and 75 valve 57 into reaction chamber 41.

Chamber 41 is also preferably maintained at a substantial superatmospheric pressure and, al- 75 though not indicated in the drawing, this zone is

preferably insulated in order to prevent the ex-cessive loss of heat by radiation so that the heated products supplied thereto, and more particularly their vaporous components, are subjected therein to appreciable further conversion. In the par- 5 ticular case here illustrated, both vaporous and liquid conversion products are withdrawn in com- mingled state from the lower portion of chamber 10 41 and directed through line 58 and valve 59 into chamber 40. It is, however, also within the scope 15 of the invention, although not illustrated, to sepa- 20 rately remove vaporous and liquid conversion products from chamber 41, supplying the latter either alone or together with a regulated portion 25 of the vapors to chamber 40, in the manner de- 30 scribed, while the vaporous products may be sepa- 35 rately supplied, all or in part, to chamber 40 or supplied, all or in part direct to fractionator 48.

Chamber 40 is preferably maintained at a sub- 20 stantially reduced pressure relative to that em- 30 ployed in reaction chamber 41 by means of which appreciable further vaporization of the liquid product supplied to this zone from the reaction chamber is accomplished. Residual liquid re- 35 maining unvaporized in chamber 40 may be with- 40 drawn through line 60 and valve 61 to cooling and storage or elsewhere, as desired. It is also within the scope of the invention, when desired, to operate chamber 40 as a coking zone wherein the heavy residual components of the conversion 45 products supplied thereto are reduced to coke. When this method of operation is employed the coke may be allowed to accumulate within cham- 50 ber 40 to be removed therefrom after opera- 55 tion of the chamber is completed and, when desired, a plurality of coking chambers may be em- 60 ployed for this purpose, although not illus- 65 trated, and preferably are alternately operated, 70 cleaned and prepared for further operation. Va- 75 porous products are removed from the upper por- 80 tion of chamber 40 and directed through line 62 85 and valve 63 to fractionation in fractionator 48.

The components of the vaporous products sup- 45 plied to fractionator 48 boiling above the range 50 of the desired final light distillate product of this stage of the system are condensed within the fractionator as reflux condensate which may be re- 55 moved from the lower portion thereof through line 49 and valve 50 to pump 51 by means of which it is returned through line 27 and valve 52 to 60 further cracking in heating coil 54.

Fractionated vapors of the desired end boiling point are removed, together with uncondensable gas, from the upper portion of fractionator 48 and 65 directed through line 64 and valve 65 to condensa- 70 tion and cooling in condenser 66. The resulting distillate and uncondensed gases pass through line 67 and valve 68 to collection and separation 75 in receiver 69. Distillate may be withdrawn from receiver 69 through line 70 and valve 71 to storage, 80 or elsewhere, as desired. The gases may be re- 85 leased from receiver 69 through line 72 and valve 73. When desired, regulated quantities of the distillate collected in receiver 69 may be recircu- 90 lated by well known means (not shown) to the 95 upper portion of fractionator 48 to serve as a refluxing and cooling medium in this zone for as- 100 sisting fractionation of the vapors and to main- 105 tain the desired vapor outlet temperature there- 110 from.

The high boiling fractions of the commingled oils supplied to column 6, including high boiling components of the charging stock and any residual liquid conversion products and heavy poly- 115 merization products from heating coil 19, are 120

removed from the lower portion of column 6 through line 28 and valve 29 to pump 30 by means of which they are fed through line 31 and may be directed, all or in part, either through valve 32, 5 in this line, to heating coil 33 or, all or in part, through line 44, valve 47 and either through valve 45 in this line into reaction chamber 41 or through line 42, valve 43, line 36 and valve 38 into the upper portion of chamber 40 or from line 36 10 through line 37 and valve 39 into the lower portion of chamber 40 or, when desired, regulated quantities of the relatively high boiling oils may be supplied to any two or more of the points mentioned.

15 When supplied to reaction chamber 41 the high boiling oils from column 6 commingle with the heated products from heating coil 54 and are subjected therewith to relatively mild cracking in the reaction chamber. When supplied to chamber 40 the high boiling oil from column 6 may be subjected to further vaporization in this zone either by virtue of a reduced pressure in chamber 40 relative to that employed in column 6 or, due to the heat recovered by the heavy oils from the 20 conversion products supplied to chamber 40 from reaction chamber 41, or in part by both. In the latter case non-vaporous high boiling components of the heavy oils supplied to chamber 40 will be recovered from this zone, together with the residual 25 liquid conversion products removed therefrom as previously described, without being subjected to appreciable cracking.

When heating coil 33 is employed the relatively high boiling oil supplied thereto from column 6, 30 as previously described, is heated to the desired cracking temperature, preferably at a substantial superatmospheric pressure by means of heat supplied from a furnace 34. The heated products are directed from heating coil 34 through line 36 35 and may be directed either through valve 38 in this line into the upper portion of chamber 40 or through line 37 and valve 39 into the lower portion of chamber 40 or, when desired, they may pass, all or in part, from line 36 through line 42, 40 valve 43, line 44 and valve 45 into reaction chamber 41.

Two general methods of operation may be employed in heating coil 33, depending primarily upon the characteristics of the relatively heavy 45 oils supplied thereto and the residual conversion product of the process which it is desired to produce. When the oil supplied from heating coil 33 from column 6 is of a relatively high boiling nature and it is desired to produce coke as the final residual product of the process, the oil is 50 preferably heated in coil 33 to a high conversion temperature and, although illustrated in a conventional manner in the drawing, coil 33 and furnace 34 are preferably of such form, which is now well known, that the oil is quickly heated 55 without allowing it to remain in the heating coil and communicating lines for a sufficient length of time to permit any substantial formation and deposition of coke therein. When this method of operation is employed the heated products 60 from coil 33 are supplied to chamber 40, wherein the coke is allowed to accumulate.

When it is desired to produce good quality fuel oil as the residual product of the process but 65 the high boiling oils removed from the lower portion of column 6 are too viscous to meet the desired market specifications, heating coil 33 may be operated as a viscosity breaking coil, in which case a relatively low cracking temperature and 70 a relatively long conversion time is preferably 75

employed in this zone. In such cases the heated products from coil 33 may be supplied either to vaporizing chamber 40 or to reaction chamber 41, as desired. When supplied to the reaction chamber the heavy oils from coil 33 are subjected to 5 additional conversion time, under the relatively mild cracking conditions maintained in this zone, before being supplied therefrom to chamber 41.

The preferred range of operating conditions which may be employed to produce the desired results in an apparatus such as illustrated and above described are approximately as follows: The heating coil to which reflux condensate and intermediate fractions of the liquid conversion products and of the charging stock are supplied 10 may employ an outlet conversion temperature ranging, for example, from 850 to 975° F., preferably with a superatmospheric pressure at this point in the system of from 100 to 500 pounds, or thereabouts, per square inch. The succeeding reaction chamber may utilize a superatmospheric pressure substantially the same or somewhat lower than that employed at the outlet from the heating coil. The vaporizing or coking chamber is 15 preferably operated at a substantially reduced pressure relative to that employed in the reaction chamber which may range, for example, from a superatmospheric pressure of 100 pounds, or thereabouts, per square inch, down to substantially atmospheric pressure. The fractionating, condensing and collecting equipment of this stage 20 of the system may employ pressures substantially the same or somewhat lower than that employed in the vaporizing or coking chamber. The reforming coil to which regulated quantities of the motor fuel product from the distilling and reforming operations are supplied preferably employs an outlet conversion temperature of the order of 925 to 1000° F., or more, and a superatmospheric pressure of from 200 to 1000 pounds, 25 or thereabouts, per square inch. The succeeding separating and fractionating zone is preferably operated at a substantially reduced pressure relative to that employed at the outlet from the reforming coil which may range, for example, from 30 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

As a specific example of the operation of the process, a Mid-continent crude of about 30° A. P. I. gravity containing approximately 18% of material boiling up to 400° F. is subjected to fractional distillation by commingling the same in the separating and fractionating column of the system with heated products from the reforming coil. The light distillate product from the topping and reforming operations is a motor fuel of approximately 400° F. end boiling point and a sufficient quantity of this product is recycled through the 75

reforming coil to bring the anti-knock value of this product up to an octane number of 70 or better. A cracking temperature of approximately 985° F. and a superatmospheric pressure of about 800 pounds per square inch is employed at the outlet from the reforming coil. The heated products from the reforming coil passing to the separating and fractionating column are cooled by commingling therewith a sufficient quantity of the charging stock to reduce their temperature to approximately 750° F. Intermediate fractions from the separating and fractionating column, which have an end boiling point of approximately 690° F., are supplied to a separate cracking coil wherein they are heated to an outlet conversion temperature of approximately 940° F. at a superatmospheric pressure of about 350 pounds per square inch. This pressure is substantially equalized in the succeeding reaction chamber and the products from this zone are supplied to a coking chamber wherein their high boiling components are reduced to coke. Vaporous products from the last mentioned cracking and coking operation are subjected to fractionation for the formation of reflux condensate which is returned to the last mentioned cracking coil and the light distillate product from this stage of the system comprises a motor fuel of approximately 390° F. end boiling point having an octane number of approximately 70. The high boiling oils from the separating and fractionating column are quickly heated in another separate cracking coil to an outlet conversion temperature of approximately 950° F. at a superatmospheric pressure of about 100 pounds per square inch and are introduced into the coking chamber which is maintained at a superatmospheric pressure of approximately 30 pounds per square inch. This pressure is substantially equalized in the succeeding fractionating, condensing and collecting portions of the system and substantially the same

pressure is employed in the separating and fractionating column. The yield of motor fuel from this operation is approximately 63% based on the charging stock, and the coke produced, which is of low volatility and good structural strength, amounts to approximately 75 pounds per barrel of crude charging stock, the remainder being chargeable, principally, to uncondensable gas. 5

I claim as my invention:

1. In a conversion process wherein hydrocarbon oil is heated to cracking temperature under pressure in a heating coil, the heated products separated in a separating chamber into vapors and residue and the former fractionated in a fractionating zone to condense heavier fractions thereof, the method which comprises simultaneously topping and fractionating crude oil containing straight-run gasoline in a second fractionating zone to separate the gasoline therefrom and to form topped crude and an intermediate fraction heavier than gasoline, passing a portion of the gasoline through a second heating coil and heating the same therein sufficiently to enhance its anti-knock value, introducing resultant products to the second fractionating zone to supply heat for the topping and fractionation of the crude, removing said intermediate fraction from the second fractionating zone and combining the same with reflux condensate formed in the first-named fractionating zone, supplying the resultant mixture to the first-named coil, removing topped crude from the second fractionating zone and combining the same with said heated products from the first-named coil for separation therewith in the separating chamber into vapors and residue. 10 15 20 25 30 35

2. The method as defined in claim 1 further characterized in that the topped crude is heated to cracking temperature in a third heating coil prior to its commingling with said heated products from the first-named coil. 40

ALVIN ENGELSTEIN.
